UNITED STATES PATENT OFFICE.

CALVIN M. FITCH, OF CHICAGO, ILLINOIS.

ORE-CONCENTRATING MACHINERY.

SPECIFICATION forming part of Letters Patent No. 450,063, dated April 7, 1891.

Application filed December 26, 1890. Serial No. 375,801. (No model.)

To all whom it may concern:

Be it known that I, CALVIN M. FITCH, a citizen of the United States, residing at Chicago, in the county of Cook and State of Illinois, 5 have invented certain new and useful Improvements in Ore-Concentrating Machinery, of which the following is a description, reference being had to the accompanying drawings, and to the letters of reference marked 10 thereon, which form part of this specification.

My invention relates to the concentration of pulverized ore and the separation of the heavier metallic or metalliferous particles from the lighter and worthless quartz or 15 gangue, apparatus embodying its leading features being adapted to rapidly, economically, and thoroughly perform the work of concentration and separation either with or without the employment of water with the pulverized 20 ore to be manipulated.

In general terms the machine embraces a single or multiple arrangement of suitably sustained and actuated trays or like receptacles provided with a grating or series of suit- 25 ably-distanced plates (the latter being the preferred form of device) within the tray, adapted through their peculiar operative arrangement to control the passage of and manipulate the material between the points of ore-supply and

30 gangue-discharge in such manner that the heavy metalliferous constituents are separated from the gangue or worthless quartz and caused to settle and pass beneath the plates to a common discharging-point pro- 35 vided in the bottom in the direction from which they may be drawn off, while the worthless matter is caused to pass over the grating or plates to the point of discharge provided therefor.

40 The machine embraces other features of novelty and utility, all of which are herein-after fully described, and pointed out in the appended claims.

In the drawings, Figure 1 represents in longitudinal section a concentrating-machine embodying in longitudinal multiple form the series of plates and other features of my invention. Fig. 2 is a top plan view of said machine, mechanism for actuating the same 45 being shown. Fig. 3 is an end elevation of the apparatus, likewise showing means for

oscillating or reciprocating the same. Fig. 4 is a transverse section of the machine, the proportions being somewhat changed, taken on the line Y Y of Fig. 2. Fig. 5 is a 55 longitudinal sectional detail showing a modification of certain of the details of the machine shown in the said above-described views. Fig. 6 is a view in transverse section of another form of multiple machine 60 embodying the features of my invention. Fig. 7 illustrates in top plan view a single tray provided with a grating or longitudinal and transverse plates E in contradistinction to a single series of plates shown in the other views. 65 Fig. 8 illustrates in top plan detail a form of indicator which I desirably employ in conjunction with the rod of the valve shown, which controls the concentrates-outlet for registering the operative position of the valve 70 with relation to its seat. Fig. 9 is a detail in side elevation of the upper portion of the valve-rod and the bearing for the same, together with the indicator connected therewith, shown in Fig. 8. Fig. 10 is a detail in 75 transverse section of a single tray particularly intended to show a modified arrangement of the bottom of the ore-containing receptacle with reference to the concentrates-outlet.

80 Referring by letter to the details of construction shown in the several described views, A indicates the tray, the bottom *a* of which inclines downwardly, desirably from every direction, toward a common converging point, 85 at or about which is located an outlet *a'* (hereinafter referred to as "inferior discharge") for the withdrawal of the concentrates, the said outlet being preferably in the form of an inverted cone, and being provided with a valve *B* of corresponding form carried by a rod *B'*, operatively sustained by a bracket or bar *B*², extended athwart the upper portion of the tray. The said inferior discharge ordinarily forms the lower terminal of a receptacle *A'*, 95 depending from the lowest extremity of the bottom of the tray, the receptacle being integral of or fixed to the tray, and being adapted to primarily receive the mineral therefrom, and being operatively separated from the 100 working area thereof by a screen or perforated diaphragm *a*². The sides of the tray

are curved upwardly and outwardly from the inclined bottom a , forming slop-boards a^3 , hereinafter more specifically referred to.

At one end the tray is provided with a hopper C , through which the ore is supplied to the machine, the opposite end being provided with a waste-outlet, as D , hereinafter referred to as "superior discharge."

The interior of the tray is provided with a grating or series of plates E , formed of any suitable material, projected across the area thereof in the direction of its line of motion and extended downwardly in the direction of the bottom a to a common horizontal plane, as shown particularly in Fig. 1, or upon one or more longitudinal planes corresponding desirably with the plane, planes, or form of the said bottom, as shown sufficiently in Fig. 5, in every instance the plates being projected downwardly only for such distance as shall leave suitable space, for the purpose hereinafter particularly described, between their respective lower edges and the said bottom, the upper edges of said plates being preferably upon a common plane coincident with the plane of the superior discharge D . The said plates at or near their lateral extremities adjacent to the slop-boards a^3 , increase in vertical proportion, so as to form (or are provided with) pulp-guides e , which, being fixed to the slop-boards, project upwardly toward the top thereof.

The hopper C is provided with an outlet c , arranged to discharge the pulp into the working area of the tray ordinarily below the plane described by the upper margins of the plates E .

C' indicates a perforated water-supplying cylinder located within the hopper C and connected by flexible tubing c' with a source of supply, said cylinder being adapted by means of the perforations c'' , formed in its circumference, to feed water to the pulp contained within the apparatus, as may be desired.

The valve-rod B' , near its upper end, is provided with a screw-thread b , which works within a corresponding bearing b' , formed or carried by the transverse bar B^2 , the end of the rod carrying an operating hand-wheel B^3 . To the top of the bearing b' is horizontally fixed a stationary disk B^4 , preferably having a convexed perimeter and provided with digits, lines, or the like, substantially as shown, equispacing its circumference.

From the hand-wheel B^3 is downwardly projected a cylindrical stem b^3 , which carries a small loose wheel b^4 , having its periphery concaved, so as to work snugly upon the perimeter of the disk. The stem b^3 , being arranged to play freely through the center of said wheel b^4 , enables the wheel to traverse the circumference of the disk without being drawn from its operative contact with its perimeter as the stem moves upwardly or downwardly, consequent upon the hand-wheel being rotatively moved to regulate, through the withdrawal or forward motion of the screw, b ,

the position of the valve with relation to its seat, which is indicated by the position to which said wheel b^4 is brought with relation to said digits, lines, &c., provided on the disk. A set-screw b^5 is shown in Fig. 9 to be employed in connection with the bearing b' for fixing the valve-rod in position; but other means may be employed for such purpose—as, for example, a set-nut working upon the screw b above or below its bearing, as described.

The machine is shown to be sustained by rods F , connected by their lower ends with the apparatus and by their upper ends with an overhead frame-work R , being capable of adjustment in the direction of their length, so as to enable the regulating of the plane upon which the apparatus shall work. The preferred means for effecting such adjustment are shown to consist of screw-threads f and nuts $f' f^2$, provided at the upper ends of the sustaining-rods.

Means for giving motion to the machine are shown in Figs. 2 and 3, which illustrate a crank-disk G , fixed to a rotary shaft j , to which motion is given through a pulley J by a belt I , the crank-disk being connected with the suspended machine by means of a pitman H .

In Figs. 5 and 10 the receptacle A' and screen a^2 are shown to be dispensed with, the mineral being thereby enabled to pass directly from the bottom of the tray to and through the inferior discharge a' .

In Fig. 6 is illustrated a multiple machine in which the trays are connected laterally of each other. In this construction the plates E are shown to extend across the combined area, the pulp being allowed to pass from one tray or compartment to the other as the apparatus is given motion. In other particulars this form of apparatus is arranged and operated substantially similarly to a single tray, the lower ends of the sustaining-rods being connected with a frame-work P , which carries the apparatus.

In a multiple arrangement of the apparatus, wherein the trays are connected in longitudinal series, as shown particularly in Figs. 1, 2, and 5, the gangue outlet or superior discharge is provided in some form at the terminal end of the last tray of the series, the partition between trays forming or being provided with means for permitting overflow of pulp from one tray to the next, the overflow being upon or about the plane of the upper margins of the plates E and the superior discharge D , and the discharge into trays, subsequent to the first, being desirably below said plane in a manner similar to that described with reference to the discharge of ore from the hopper C . The preferred means for effecting the discharge of the overflow in such manner is a downwardly-inclined hood k , suitably connected with an opening k' , provided in the partition K between trays. (See particularly Figs. 1 and 5.)

When water is used for concentrating the

ore, the machine is adjusted so that it inclines downwardly in the direction of its length, say, from one-eighth inch to one-half inch (more or less) per lineal foot between the points of ore-supply and gangue-discharge, the inclination when the ore is treated in a dry state being, say, from one inch to three inches (more or less) per lineal foot.

- The following description of a machine in multiple arrangement, as shown in Fig. 1, the ore being treated by the wet process, is deemed a sufficient exposition of the utility of the invention. The machine being set in motion, the pulp fed into the hopper is discharged through the opening *c* thereof into the first tray below the plane of the upper edges of the plates *E*, the rapid oscillation or reciprocation of the apparatus tending to keep the mass in a thoroughly mixed and softened condition and facilitating the tendency of the heaviest particles or mineral to settle toward the bottom. The pulp gradually filling up the working area of the first tray is prevented from rapidly moving in the direction of the outlet *k'* by the plates *E*, between and against which it works, the heavy mineral so interrupted in its longitudinal passage being shaken or moving by reason of its greater specific gravity toward the sloping bottom and following the same beneath the plates toward the inferior discharge *a*, the lighter and less rich pulp working upwardly toward the upper edges of the plates, over which it gradually passes in the direction of the overflow-outlet, its contained particles of mineral being intercepted by subsequent plates before reaching the outlet or passing with the gangue into the subsequent tray, within which the concentrating treatment is repeated, and so on until the superior discharge is reached. It is obvious that if any particles of mineral settle in the mass of pulp between the plates for a distance however slight below the plane of their upper edges these particles must either rise toward the surface against the force of gravity or settle downwardly toward the main body of the mineral. It may be further noted that the curved form given to the sides of the tray to form the slop-boards *a'* permits free lateral movement of the material under treatment as the apparatus is oscillated or reciprocated, thereby avoiding the undue splashing or slopping which would be incident to the employment of perpendicular or angularly-inclined sides; also, that the pulp-guides *e* prevent the material which travels up the slop-boards from slopping over the plates *E*, except at the point (*i. e.*, between said guides) intended for such purposes, the said guides likewise determining the length of the upper working-edges or faces of said plates, over which the light pulp or gangue passes. The valve being adjusted so as to open the inferior discharge *a*, the concentrates flow through said discharge while the machine is in motion in a steady and uniform stream, limited in its volume neces-

sarily by the degree of opening or closure of the discharge. The receptacle *A'* and its auxiliary screen or perforated diaphragm being employed, the reciprocation of the machine causes the mineral forming the lowest stratum of the concentrates to continuously slide to and fro over the screen or diaphragm, the mineral being gradually sifted through its openings or perforations into the receptacle in such quantity as the discharge from the outlet *a* will admit. When by the adjustment of the valve the discharge of mineral from the outlet is of limited volume compared with the amount fed with the pulp into the tray, there will obviously be gathered in the deepest portion of the tray a bed of mineral, richest (because heaviest) at its lowest stratum, the discharge therefore being exclusively of rich mineral. Conversely when the discharge is of large volume comparatively there will necessarily be a greater or less proportion of gangue drawn off with the mineral, and the concentrates will be of lower grade. By the adjustment of the valve to control the discharge through the outlet manifestly the operator is enabled to regulate the richness of the concentrates.

I claim as my invention and desire to secure by Letters Patent—

1. In ore-concentrating apparatus, a suitably-sustained tray having a downwardly-inclined bottom, a concentrates-receiving receptacle depending from said bottom, provided with an outlet for the discharge of the concentrates, a screen or perforated diaphragm separating the receptacle from the area of the tray through which the concentrates pass to said receptacle, and means for oscillating or reciprocating the apparatus, substantially as described.

2. In ore-concentrating apparatus, a suitably-sustained tray having a downwardly-inclined bottom, a concentrates-receiving receptacle depending from said bottom, provided with an outlet for the discharge of the concentrates, a screen or perforated diaphragm separating the receptacle from the area of the tray through which the concentrates pass to said receptacle, a valve for controlling the discharge from the concentrates-outlet, and means for oscillating or reciprocating the tray, substantially as described.

3. In ore-concentrating apparatus, a suitably-sustained tray having a grating or series of plates projected across its working area, extending downwardly in the direction of but separated from its bottom, arranged and adapted to allow the gravitating concentrates to pass intermediate of their lower margins and the bottom of the tray toward a common discharge and the gangue to pass over their upper portions to discharge, an outlet connected with said bottom for discharging the concentrates, and means for oscillating or reciprocating the apparatus, substantially as described.

4. In ore-concentrating apparatus, a suit-

ably-sustained tray having within its working area a series of plates projected in the direction of its line of motion and extended downwardly in the direction of but separated from its bottom, arranged and adapted to allow the concentrates to pass beneath their lower margins toward a common discharge and the gangue to pass over their upper portions to discharge, pulp-guides at or about the extremities of said plates, an outlet for the discharge of the concentrates, and means for oscillating or reciprocating the tray, substantially as described.

5. A suitably-sustained ore-concentrating tray having a downwardly-inclined bottom and slop-boards extended upwardly therefrom, a discharge for the concentrates connected with the bottom thereof, a series of plates projected across its working area in the direction of its line of motion and extended downwardly in the direction of but separated from said bottom, arranged and adapted to allow the concentrates to pass beneath their lower margins toward a common discharge and the gangue to pass over their upper portions to discharge, pulp-guides at the extremities of said plates operatively connected with the slop-boards, and means for oscillating or reciprocating the tray, substantially as described.

6. A suitably-sustained concentrating-tray having a downwardly-inclined bottom, an outlet connected with said bottom for discharging the concentrates, a series of plates projected across the working area of the tray in the direction of its line of motion, extended downwardly in the direction of but separated from its bottom, arranged and adapted to allow the concentrates to pass beneath their lower margins toward a common discharge and the gangue to pass over their upper portions to discharge, means for feeding pulp to the tray from one end thereof, a gangue-outlet, and means for oscillating or reciprocating the tray, substantially as described.

7. In ore-concentrating apparatus, a series of suitably-sustained laterally-connected trays having downwardly-inclined bottoms and arranged to admit of the lateral overflow or passage of the pulp from tray to tray, a discharge for the concentrates connected with the bottom of each tray, a series of plates projecting across the entire area of said trays in the direction of the line of motion of the apparatus and extending downwardly in the direction of but separated from the bottoms thereof, slop-boards forming the outer sides

of said combined trays, pulp-guides at the extremities of said plates connected with said slop-boards, and means for imparting oscillating or reciprocating motion to the apparatus, substantially as described.

8. In ore-concentrating apparatus, a series of longitudinally-connected trays having downwardly-inclined bottoms, an outlet for the concentrates connected with the bottom of each tray, a series of plates projected across the area of each tray in the direction of the line of motion of the apparatus, extended downwardly in the direction of but separated from the bottoms thereof, an outlet for permitting the overflow of pulp from tray to tray for retreatment, means for feeding pulp to the apparatus at one end thereof, a waste-outlet, suitable devices for sustaining the apparatus, and means for oscillating or reciprocating the apparatus, substantially as described.

9. In ore-concentrating apparatus, a series of suitably-sustained longitudinally-connected trays provided with inclined bottoms and slop-boards extending upwardly therefrom, a receptacle connected with the bottom of each tray, provided with an outlet for the discharge of the concentrates, a screen or perforated diaphragm separating the receptacle from the working area of the tray, a valve connected with each of the said outlets operative to control the discharge therefrom of the concentrates, a series of plates projected across the working area of each tray in the direction of its line of motion, extended downwardly in the direction of but separated from the bottom thereof, pulp-guides provided at the extremities of the plates, an outlet for the overflow of pulp from tray to tray for retreatment, means at one end of the series for feeding pulp thereto, a waste-outlet, and means for oscillating or reciprocating the apparatus, substantially as described.

10. The combination, with the concentrates-outlet, the outlet-controlling valve, its screw-threaded rod or stem, the hand-wheel attached to the outer end thereof, the screw-bearing, and the stationary disk provided with digits, lines, or the like, of the cylindrical stem projecting from the hand-wheel and the loose indicator-wheel carried thereby, adapted to traverse the perimeter of the disk, in the manner and for the purpose set forth.
